C. H. LICHT.

GRAIN DOOR.

APPLICATION FILED FEB. 4, 1922.

1,432,879.

Patented Oct. 24, 1922.

UNITED STATES PATENT OFFICE.

CARL H. LICHT, OF RUSHMORE, MINNESOTA.

GRAIN DOOR.

Application filed February 4, 1922. Serial No. 534,084.

To all whom it may concern:

Be it known that I, CARL H. LICHT, a citizen of the United States, residing at Rushmore, in the county of Nobles and State of Minnesota, have invented certain new and useful Improvements in Grain Doors, of which the following is a specification, reference being had to the accompanying drawings.

10 The present invention has for its purpose the provision of a grain door for grain cars, wherein means is afforded for urging pressure upon the door, at a point substantially midway the upper and lower edges of the 15 door at its ends, for the purpose of holding the door securely in place, and for resisting the pressure of the grain on the interior of the car.

Another purpose is the provision of a 20 grain door including normally arcuately shaped bars or rods connected to the car body at points below the door opening and adjacent the ends of the door, said bars normally bowed for urging against the sections of the door, to hold the parts of the door in place and to prevent rattling of the door due to the vibration of the car.

Still another purpose has to do with connecting the lower ends of the rods or bars 30 to the car body at points below the door opening, so as to permit outward movement of the rods, whereby the sections of the door may be easily removed.

A further purpose has to do with the provision of split or forked ends at the upper 35 portions of the rods, for the purpose of engaging bolts, to hold the rods in position, and to cause them to urge against the door sections, there being washers and nuts applied to the bolts to hold the split or forked ends of the rods in position.

While the design and construction at present illustrated and set forth are deemed preferable, it is obvious that as a result of 45 a reduction of the invention to a more practical form for commercial purposes, the invention may be susceptible of changes and the right to these changes is claimed, provided they are comprehended within the 50 scope of what is claimed.

The invention comprises further features and combination of parts, as will be hereinafter set forth, shown in the drawings and claimed.

In the drawings:—

Figure 1 is a view in elevation of a portion of a grain car, showing the improved grain door holding means applied, for holding the grain door in place; 55

Figure 2 is a vertical sectional view on line 2—2 of Figure 1, showing the rods in position, and showing them disposed outwardly in dotted lines with their upper ends loosened; 60

Figure 3 is an enlarged detail view of the attaching plate for connecting the lower end of a rod to the car; 65

Figure 4 is a detail view of one of the door sections; and

Figure 5 is a sectional view on line 5—5 of Figure 1. 70

Referring to the drawings, 1 designates a grain car, which has a grain door opening 2, and 3 denotes the door, which comprises a plurality of sections 4. The ends of the 75 sections of the door are provided with cleats 5, which connect the ends of the slats of the door sections, for the purpose of holding the slats relatively in position.

Secured to the lower portion of the car 80 adjacent the lower edge of the door opening are plates 6, which have slots 7, which are T-shaped in cross-section. One end of the slot of each plate is closed by the wall 8, thereby preventing downward movement of 85 the door holding means.

The door holding means comprises a pair of rods 9, the lower ends of which have transverse heads 10, which engage the slots 7 of the plates 6. The rods 9 are constructed 90 of spring metal, such as steel, and are bowed or arcuately shaped as illustrated in dotted lines, before they are held in their final positions to exert pressure on the door sections. The upper ends of the rods 9 are forked or 95

split as shown at 11, and the arms caused to be formed by the split or bifurcation straddle bolts 12, which project from the side of the car adjacent the upper part of the door opening. Suitable washers 13 are applied to the bolts 12, and threaded upon the bolts are nuts 14, which bear against the washers, which in turn bear upon the forked or split ends of the rods, in order to hold them in place. 100

In fact when the door sections are positioned in the door opening, the normally arcuately shaped rods are moved toward 105

and in contact with the door sections, so that they will apply pressure on all sections of the door, when the sections are in position, for the purpose of holding them in place.

5 By loosening the nuts the upper ends of the rods will swing outwardly, in fact the entire length of the rods will swing outwardly, leaving the door sections free to be moved, by first removing the top section, 10 then the next section, and then the lower section. In fact the top section may first be removed, and the next two sections raised, and then if desired the rods may be again clamped in position. In this way the remaining sections will be held in place, leaving an opening at the bottom previously closed by the lower section, allowing the grain to flow from the lower part of the opening. This may be done, until the 15 greater bulk of the grain is removed, then 20 all of the sections may be removed by loosening the holding rods.

The invention having been set forth, what is claimed is:—

The combination with a grain car having a door opening, of a grain door mounted in said opening, a pair of members secured to the car body at points below the opening and adjacent its ends, said members having slots T-shaped in cross section, a pair of normally bowed spring rods having T-shaped lower ends engaging said slots for detachably connecting the rods to the members, the upper ends of the rods having forks, bolts projecting outwardly from the car body at points above the door opening and adjacent its ends and which are straddled by the forks, washers upon the bolts, and means on the bolts for holding the forked ends in place. 25 30 35 40

In testimony whereof I hereunto affix my signature.

CARL H. LICHT.
